UNITED STATES PATENT OFFICE

148,203

DESIGN FOR A VEGETABLE CUTTER
OR THE LIKE

THERON H. WALKER, LOS ANGELES, CALIF.

Application May 4, 1946, Serial No. 129,346

Term of patent 14 years

(Cl. D89—1)

To all whom it may concern:

Be it known that I, Theron H. Walker, a citizen of the United States, residing in the city of Los Angeles, in the county of Los Angeles and State of California, have invented a new, original, and ornamental Design for a Vegetable Cutter or the like, of which the following is a specification, reference being had to the accompanying drawing, forming part thereof.

Fig. 1 is a front perspective view of a vegetable cutter or the like showing my new design, with the knife carrier and presser plate in lowered position.

Fig. 2 is a rear perspective view with the parts in the same position as Fig. 1.

Fig. 3 is a front perspective view showing the knife carrier in an elevated position.

Fig. 4 is a side view in elevation with the presser plate in elevated position.

I claim:

The ornamental design for a vegetable cutter or the like, substantially as shown.

THERON H. WALKER.
